UNITED STATES PATENT OFFICE

105,432

DESIGN FOR A COAT OR SIMILAR ARTICLE

Irving Cohen, New York, N. Y.

Application June 21, 1937, Serial No. 69,955

Term of patent 3½ years

To all whom it may concern:

Be it known that I, Irving Cohen, a citizen of the United States of America, residing in Manhattan, county of New York and State of New York, have invented a new, original, and ornamental Design for a Coat or Similar Article, of which the following is a specification, reference being had to the accompanying drawing, forming part thereof, wherein,

The characteristic feature of my design resides in the combination on the cloth coat as shown, of four fur bands on each of the bell sleeves in association with a fur collar of the instant configuration.

I claim:

The ornamental design for a coat or similar article, substantially as shown and described.

IRVING COHEN.
